UNITED STATES PATENT OFFICE.

PAUL M. RAINY, OF WEST HOBOKEN, NEW JERSEY, ASSIGNOR TO WESTERN ELECTRIC COMPANY, OF NEW YORK, N. Y., A CORPORATION OF ILLINOIS.

VIBRATING CIRCUIT-BREAKER.

1,090,877.

Specification of Letters Patent. Patented Mar. 24, 1914.

Application filed June 17, 1910. Serial No. 567,451.

To all whom it may concern:

Be it known that I, PAUL M. RAINY, a citizen of the United States, residing at West Hoboken, in the county of Hudson and State of New Jersey, have invented a certain new and useful Improvement in Vibrating Circuit-Breakers, of which the following is a full, clear, concise, and exact description.

- 10 This invention relates to automatic vibrating circuit breakers, such as are used with induction coils and vibrating bells, to continuously make and break the circuit in which they are included.
- 15 The object of this invention is to provide a slow-moving vibratory circuit breaker which will vibrate at approximately its normal rate, immediately upon closing the circuit, as distinguished from similar prior 20 structures having weighted armatures which start slowly and gradually increase their vibratory movement until the normal rate is attained.

With this improved device the temporary 25 short closure of the circuit, as in depressing a button to signal, is effective to transmit current impulses having the predetermined, necessary, maximum electromotive force and desired frequency. The result is attained 30 by substituting a device employing air friction as a regulating means in place of inertia due to mass. To this end the vibrator is provided with an armature in the form of a long broad vane supported at one 35 end and passing intermediate its ends through the field of force of the induction coil, the circuit of which the said vane is adapted to intermittently open and close.

The accompanying drawings illustrate the 40 invention.

Figure 1 is a front elevation of the vibrating contact; Fig. 2 is a side elevation, partly in section, showing an induction coil and its two electrical contacts forming the vibrating circuit breaker.

The induction coil *i* has the usual primary coil *p*, and secondary coil *s*. The electrical contacts forming the circuit breaker for this induction coil consist of an electrical contact 45 *c* in the form of a spring fixed in position by

screws *b*, while the vibrating contact *a* is suitably insulated, as at *q*, and held by the same screws *b*. This vibrating contact *a* is novel and consists of a thin plate of magnetic metal, such as sheet iron, arranged 55 vertically in the plane of the pole piece *r* and extending within and through the field of force of said pole piece. The plate *a* is designed and constructed to have comparatively extended superficial area with 60 small mass or gravity, the object being to so construct the fan or vane that while it will reach its normal rate of vibration immediately the air presents resistance thereto and affords regulation of its vibrating 65 movement. It results from this construction that upon closing a circuit through the primary winding *p* for a brief interval only, the vane *a* starts into its approximately normal rate of vibration quickly; and yet, due 70 to the retarding action of the air upon the broad vane, this period may be relatively low.

What I claim and desire to secure by Letters Patent is:

1. An interrupter comprising an induction coil, an armature, a support for said coil and armature, said armature being in the form of a long broad vane anchored at one end to said support and passing through 80 and beyond the field of force of said coil, and a circuit including said coil adapted to be opened and closed by said armature in its movement.

2. An interrupter comprising an induction coil, an armature, a support for said coil and armature, said armature being in the form of a long broad vane anchored at one end to said support and passing near 85 its anchored end through and extending beyond the field of force of said coil, and a circuit adapted to be opened and closed by said armature in its movement.

In witness whereof, I, hereunto subscribe my name this 16th day of June A. D., 1910. 95

PAUL M. RAINY.
